UNITED STATES PATENT OFFICE

2,454,816

POTENTIOMETER

Maurice Moise Levy, London, England, assignor
to International Standard Electric Corporation,
New York, N. Y., a corporation of Delaware

Application October 22, 1946, Serial No. 704,972
In Great Britain February 14, 1946

1 Claim. (Cl. 201—55)

1

This invention relates to electrical potentiometers, and its object is to provide a potentiometer having a fine control of tapped resistance.

According to the invention an electrical potentiometer comprises a resistance arranged in spiral form, a contact movable backwards and forwards along the spiral resistance, stationary terminals for both ends of the resistance, and a stationary terminal with which the movable contact is in electrical connection throughout its path of travel to and fro along the spiral resistance.

The invention will be fully understood from the following description of one embodiment thereof shown in the accompanying drawings in which:

Figure 1 shows a potentiometer in cross-sectional elevation; and

Figure 2 shows detached views in plan and elevation of cursor arm and feeder wiper.

The base of a moulded Bakelite potentiometer 1 is centrally apertured to receive a spindle 2 to which is fixed a bush 25 with a screw-threaded extension 4. The aperture 21 has a peripheral groove 22 complete except for a locking key 23 which engages a cut-away slot in a flange on the bush 25 seating in the groove 22. The bush and spindle are fixed in the potentiometer 1 by a hexagon nut 3.

On the spindle 2 above the bush 25 are fixed a Bakelite radial arm 5 and a Bakelite disc 6. The arm 5 carries a cursor 16 engaging a roughly spiral groove 17 in the base of potentiometer 1. The ends of the groove positively limit the maximum possible rotation; about 650°, of the arm and the Bakelite disc.

The Bakelite disc 6 carries a spring metal member 7 constituting a feeder wiper and a cursor-carrier. The member 7 is shown separately in Figure 2 and comprises a two-armed base portion 26 fixed to the disc 6. Integral with the middle of the base 26 is a long arm 7 which is bent over radially so as to be spaced from the disc 6 and then doubled under at 27 to rest on the disc to which it is fixed. The two arms of the base 26 also have extensions bent backwards above the base and shaped to engage and wipe over a fixed contact disc 13 fixed in a Bakelite lid 9 for the pot 1. A cursor 8 is slidably mounted on the arm 7.

The lid 9 rests on a ledge 18 in the pot 1 and is fixed in position by a flat spring 10 engaging a groove 20 in the rim of the potentiometer 1. The lid is held from rotation by a key 19 on the ledge 18 engaging a slot in the lid.

The underside of lid 9 is formed with a rough-

2

ly spiral raised track 11 on which is fixed a carbon resistance strip 12. Terminals 14, 15 (2 separate terminals 15 one of which is not visible in the cross-section) are mounted on the top 5 of the lid 9. The terminal 14 is riveted to the contact disc 13 and the terminals 15 to the ends of the resistance strip 12.

The cursor 8 has upstanding contact arms embracing the raised track 11 and a nipple on its 10 horizontal face engages the carbon strip 12.

It will be seen that rotation of the spindle rotates the arms 5, 7 and wiper 24. Rotation of the arm 7 causes cursor 8 to move along the spiral resistance strip 12, the cursor sliding on the arm 15 7 to the extent required by the variation in radial distance of strip 12 from the spindle axis. At the same time, wiper 24 rotates in contact with contact disc 13, so that the cursor 8 is always in electrical connection with terminal 14. Rotation 20 of the arm 5 moves the cursor 16 along the spiral slot 17, within positive limits which define the travel of cursor 8 on the carbon strip 12.

What is claimed is;

An electrical potentiometer of box-like form 25 comprising a spindle mounted axially in the box, a roughly spiral resistance element on the interior surface of one end plate, a roughly spiral guide on the interior surface of the other end plate and furnished with positive end stops, the 30 spindle carrying a rotatable assembly comprising a first radial arm carrying a first cursor co-operating with the spiral resistance strip, a second radial arm carrying a second cursor co-operating with the spiral guide, and a wiper electrically connected to the first cursor and wiping over a fixed contact disc plate mounted on the 35 end plate carrying the spiral resistance whereby there is continuous electrical connection between the resistance strip and the fixed contact 40 plate through the first cursor.
